AIR PISTOL

George E. Van Blarcom, Coldwater, Mich.

Application September 30, 1947, Serial No. 776,979

4 Claims. (Cl. 124—15)

1

This invention relates to an improved air pistol for shooting pellets or the like, and is a continuation in part of the applicant's copending application Serial No. 728,338, filed February 13, 1947, now abandoned.

The principal objects of this invention are to provide a single-shot air pistol which shoots lead pellets or the like, and which is of an extremely simple construction so as to make the manufacture of the same relatively inexpensive; to provide an air pistol of the aforementioned type in which the barrel and air cylinder are interconnected and intercommunicated so as to constitute a single assembly; to provide, in an air pistol of the aforementioned type a piston, piston rod and operating spring assembly which is easily insertible into the aforementioned cylinder so as to provide a pellet receiving and ejecting unit which is easily assembled in the hollow portion of the pistol main housing; to provide, in an air pistol of the aforementioned type, a combination piston rod and cocking lever element which is reversely looped intermediate its ends so as to provide means for cocking the piston within the cylinder; to provide in an air pistol of the aforementioned type a trigger mechanism for engaging and holding the aforementioned combination piston rod and cocking lever in a cocked position, and operable to release the same so as to shoot the pistol and project the pellet from the end of the barrel thereof; and to provide in general an improved, efficiency operating and simply constructed air pistol.

These and other objects of this invention will become apparent from the following detailed description taken in conjunction with the accompanying drawings, in which:

Figure 1 is a vertical sectional view taken through the longitudinal axis of the air pistol of this invention;

Fig. 2 is a sectional view of the structure illustrated in Fig. 1 taken substantially along the line 2—2 thereof; and

Fig. 3 is an enlarged fragmentary view of the structure illustrated in Fig. 1 taken within the circle 3 thereof.

Referring now to the drawing it will be seen that the air pistol includes a barrel 5 having a smooth longitudinally extending bore 7. The forward portion of the barrel 5 is surrounded by a barrel housing 9. A ring-like member 11 is disposed between the front end of the barrel 5 and the barrel housing 9 and has a front sight 13 formed thereon which projects upwardly through a slot 15 in the forward end of the barrel housing. The member 11 is suitably secured, as by soldering or press fitting engagement to the barrel and in the barrel housing. The extreme rear end of the barrel 5 is tapered inwardly and rearwardly at 17 to provide a slightly

2

reduced bore portion in which a pellet, which is inserted from the forward end of the barrel, will be held in preparation for being shot from the pistol, as will be hereinafter described.

The rear end of the barrel 5 projects into an aperture 21 of an end member 19, and is soldered, or otherwise suitably secured to the end member. The rear end of the aperture 21 is closed by a plug 23, which is removable to permit removal of any obstruction which may be in the barrel or in the aperture 21.

A cylinder 25 is disposed below the barrel 5 and extends substantially parallel thereto. The rear end of the cylinder 25 embraces a boss 27 of the end member 19, and is suitably secured thereto, such as by soldering. The boss 27 on end member 19 is formed with a central rearwardly extending recess or chamber 29 which communicates with the bore 31 of the cylinder 25. The recess 29 in end member, and the aperture 21, are communicably connected by a passageway 33. Thus the rear end of the barrel bore 7 is communicated with the rear end of the cylinder bore 31, and the barrel 5, barrel housing 9, end member 19 and the cylinder 25 are interconnected to form a single assembly.

A piston assembly 35 is disposed within the cylinder bore 31 and comprises, as can be best seen in Fig. 3, a rear piston 37, and a forward piston 41 which is disposed in longitudinally spaced relation with respect to the rear piston. The rear piston 37 has a rearwardly projecting boss 39 formed thereon which is adapted to be slidably received in the forward end of the recess 29, for reasons which will appear hereafter. The front piston 41 is provided with a forwardly projecting boss 43.

A reversely looped combination piston rod and cocking lever 45 has its piston rod portion 47 disposed within the cylinder bore 31. The member 45 is preferably made of wire and is reversely bent intermediate its ends to provide a loop portion 48, at the forward end of the piston rod portion 47, and a cocking lever portion 49 which extends rearwardly from the looped portion 48, parallel to the piston rod portion. The rear end of the portion 47 of the piston rod extends through aligned apertures 50 and 51 of the pistons 41 and 37, respectively. A collar 53 is formed on the piston rod 41, adjacent the rear end thereof, which abuts against the front face of the front piston boss 43. The extreme rear end of the piston rod 47 is peened over at 55 so that the piston assembly 35 is secured between the peened end and the collar 53. It will be noted that the rear end of the rear piston rod aperture 51 is countersunk at 57 so as to provide clearance between the rear end face of the piston boss 39 and the peened end 55 of the piston rod, for a reason which will hereinafter appear.

An annular, concave-convex leather packing ring 59 is disposed between the adjacent faces of the pistons 37 and 41 and has its inner periphery engaging the outer periphery of the piston rod 47. The packing ring 59 is corrugated in cross section and the rear face of the front piston 41 is provided with a groove 61 in which the ridged portions of the packing ring 59 are seated. The outer periphery of the packing ring 59 engages the wall of the cylinder bore 31 so as to prevent the flow of air around the piston assembly 35, during rearward movement of the latter.

A coil spring 63 surrounds the piston rod 47 and has its rear end embracing the front piston boss 43. The piston assembly 35, the combination piston rod and cocking lever 45 and the spring 63 thus constitute a second assembly which may be easily inserted in the above described cylinder and barrel assembly so as to provide a unit which is embraced and supported by a pistol main housing 67.

The pistol main housing 67 includes a hand grip portion 69, a trigger guard portion 71 and a hollow upper portion 73 in which is disposed the aforementioned unit. The housing 67 is formed by two housing sections, namely a right-hand section 75 and a left-hand section 77, which are split along the longitudinal axis of the air pistol. The housing sections 75 and 77 may be made of any suitable material and may be cast, stamped or the like. Each of the housing sections 75 and 77 is suitably recessed to receive the barrel housing 9, the end member 19 and the cylinder 25, so that the barrel and cylinder assembly may be positioned in one of the housing sections 75 or 77, prior to the positioning of the other housing section thereon so as to embrace the barrel and cylindrical assembly as well as the piston and cocking lever assembly. The two housing sections are secured together by any suitable means such as rivets or screws 79. The housing sections 75 and 77 are also each provided with a longitudinally extending recess 81 in which the cocking lever portion 49 is slidably received and supported. Each of the housing sections, forwardly of the recess for the cylinder 25, is provided with a reduced recess 83, within which the forward end of the spring 63 is confined, so that when the piston assembly and piston rod are pulled forwardly to cock the pistol, the spring 63 will be compressed.

In assembling the pistol, the barrel and cylinder assembly is placed in its recesses in one housing section, the cocking lever portion 49 is placed within its housing section recess 81, the front end of the spring 63 is confined in the housing section recess 83, the other housing section is placed in position, and the two housing sections are secured together by the screws or rivets 79, so as to properly embrace and confine the aforementioned assemblies.

A trigger 85 is pivotally mounted in the trigger guard portion 71 of the main housing 67 by a pin 87. The trigger 85 has a nose 89 on its front face which is adapted to engage the rear end of the cocking lever 49 so as to hold the same in its forward cocked position. The front face of the trigger 85 is provided with a second nose 91, which when the trigger is holding the cocking lever in its cocked position will abut a shoulder 92, of the trigger guard, so as to limit upward movement of the trigger with respect thereto. A hairpin-type spring 93 is connected at 95 to the trigger and has its free end engaging the under-

side of a pin 97, in the housing hand grip portion 69. The hairpin spring 93 normally tends to retain the trigger in the position shown in dot-dash lines in Fig. 1, that is, in its uppermost position so as to hold the cocking lever in its cocked position. By squeezing the lower portion of the trigger the nose 89 is moved downwardly away from the rear end of the cocking lever 49 so as to permit the cocking lever to slide rearwardly in the housing recess 81.

In operation, when it is desired to shoot the air pistol, a pellet or the like is inserted in the forward end of the barrel 5 and the pistol is tipped upwardly to cause the pellet to slide rearwardly in the barrel bore and be retained in the tapered portion 17, at the rear end thereof. The combined cocking lever and piston rod 45 is then grasped by the user at the loop 48 and pulled forwardly to the position illustrated in dot-dash lines in Fig. 1. When this occurs the piston assembly 35 is moved forwardly within the cylinder 31, and the spring 63 is compressed. The cocking lever 49 is pulled forwardly until it passes the nose 89 on the front face of the trigger, whereupon the trigger, under the action of spring 93, will move up into the recess 81 in the underside of the housing so as to engage the rear end of the cocking lever 49. The pistol is then cocked and ready for use with the pellet therein. When the trigger 85 is squeezed the cocking lever is released and the combined cocking lever and piston rod is forced to the rear by the coil spring 63, thus forcing the piston assembly 35 to the rear and compressing and forcing air rearwardly through the cylinder 31, the chamber 29, the passageway 33, and the aperture 21, into the rear end of the barrel bore 7. The air is then forced forwardly through the barrel bore 7 and shoots the pellet, under high pressure, out the front end of the barrel. The piston 37 is prevented from slapping against the portion of the end member 19 which forms the end wall of the cylinder 25 by the air which is trapped between the piston and cylinder end wall when the piston boss 39 enters the recess 29 of the end member.

The countersunk end 57 of the piston aperture 51 permits a limited amount of play between the pistons 37 and 41, when the piston assembly 35 is pulled forwardly, so as to cock the pistol. This provides a looser fit between the packing ring and cylinder bore 31 when the pistol is cocked, so as to make the cocking easier. Due to the concave-convex shape of the packing ring 59, it will efficiently seal and prevent leakage of air, when the pistol is shot.

It will thus be seen that an improved air pistol is provided in which the working parts are constructed in two assemblies, which may be easily interconnected and which can be easily connected to the main housing 67. Likewise, it will be noted that the combined piston rod and cocking lever element is inexpensive to manufacture due to its wire construction, and provides a simple and efficient means for cocking the pistol. It can thus be appreciated that the pistol herein illustrated and described is relatively inexpensive to manufacture and especially efficient in operation.

I claim:

1. An air pistol, including a barrel, a cylinder disposed below said barrel and extending substantially parallel thereto, a one-piece end member directly connected to and supporting both the rear end of the cylinder and the rear end of said barrel so as to maintain the rear barrel and cylinder portions in spaced substan-

tially parallel relationship, passageway means in said end member communicating the rear end of said barrel with the rear end of said cylinder, a piston disposed in said cylinder, cocking means connected to said piston for moving the same longitudinally in said cylinder, housing means including a handle trigger guard portion detachably embracing said barrel, cylinder and end member said cocking means including a member connected with said piston and having a portion projecting forwardly beyond the confines of said housing means for manual direct actuation, and trigger means pivotally mounted in said housing trigger guard portion and adapted to engage and hold said cocking means in a cocked position, said trigger means being operable to release said cocking means to cause said pistol to shoot.

2. An air pistol, including a barrel, a barrel housing encompassing the front portion of said barrel and connected at its forward end to the forward end of said barrel, a one-piece end member directly connected to the rear end of said barrel, a cylinder connected to said end member below said barrel so that said barrel and cylinder are positively maintained in a spaced predetermined relationship, a passageway in said end member communicating the rear end of said barrel with the rear end of said cylinder, a piston disposed in said cylinder, a rod connected to the forward end of said piston and projecting forwardly through the forward end of said cylinder, a two-piece housing including a handle trigger guard portion and a hollow upper portion in which is received and secured said aforementioned parts, a spring disposed in said cylinder and confined between the front end of said piston and said housing, said rod being reversely bent forwardly of said housing with its reversely bent rod portion extending back through and being slidably supported in said housing below said cylinder, and a trigger pivotally mounted in said housing trigger guard portion adapted to engage and hold said piston rod in a cocked position, said trigger being operable to release said piston rod to cause said pistol to shoot.

3. An air pistol, including a pellet receiving and ejecting unit, including a barrel, a barrel housing encompassing the front portion of said barrel, means securing the forward end of said barrel to said barrel housing, an end member connected to the rear end of said barrel, a cylinder connected to said end member below said barrel, a passageway in said end member communicating with the rear end of said barrel and the rear end of said cylinder, a piston disposed in said cylinder, a rod connected to the forward end of said piston and projecting outwardly through the forward end of said cylinder; a two-piece housing including a handle trigger guard portion and a hollow upper portion in which is received and secured said pellet receiving and ejecting unit, said housing including right and left-hand sections separated along the longitudinal axis of said housing, means for securing said housing sections in position so as to embrace and support said unit therein, a spring disposed in said cylinder and confined between the front end of said piston and said housing, said piston rod being reversely bent forwardly of said housing to provide means for pulling said piston forwardly within said cylinder so as to cock said pistol, said reversely bent rod portion extending back through and being slidably supported in said housing below said cylinder and above said guard

portion, a trigger pivotally mounted in said housing trigger guard portion adapted to engage and hold said piston rod in its cocked position, said trigger being operable to release said piston rod to cause said pistol to shoot a pellet therefrom.

4. An air pistol, including a pellet receiving and ejecting unit, including a barrel, a barrel housing encompassing the front portion of said barrel, means including a front sight on the forward end of said barrel housing interconnecting the forward end of said barrel and said barrel housing, a one-piece end member connected to the rear end of said barrel, the rear end of said barrel being tapered to receive and hold a pellet inserted from the forward end of said barrel, said end member having a chamber in longitudinal alignment with said barrel, a cylinder disposed below said barrel and extending substantially parallel thereto, the rear end of said cylinder being fixedly connected to said end member, said end member having a closed chamber therein in longitudinal alignment and communication with the rear end of said cylinder, a passageway in said end member between said barrel chamber and said cylinder chamber, a piston disposed in said cylinder, a rod connected to the forward end of said piston and projecting outwardly through the forward end of said cylinder; a two-piece housing including a handle trigger guard portion and a hollow upper portion in which is received and secured said pellet receiving and ejecting unit, said housing including right and left-hand sections separated along the longitudinal axis of said housing, means for securing said housing sections together so as to embrace and support said unit therein a removable, exteriorly accessible plug closing said end member barrel aligned chamber, so that said barrel may be cleaned and oiled by removing said plug, without disassembling said housing, a spring disposed in said cylinder and confined between the front end of said piston and said housing, said piston rod being reversely bent forwardly of said housing to provide means for pulling said piston forwardly so as to cock said pistol, said reversely bent rod portion extending rearwardly and being slidably supported in said housing below said cylinder and above said trigger guard portion, a trigger pivotally mounted in said housing trigger guard portion adapted to hold said piston rod in its cocked position, said trigger being operable to release said piston rod to cause said pistol to shoot a pellet out through said barrel.
